JEAN B. DUTOUR, OF SAN FRANCISCO, CALIFORNIA.

CARBURETOR.

Application filed August 14, 1920. Serial No. 403,483.

To all whom it may concern:

Be it known that I, JEAN B. DUTOUR, a citizen of the United States, and a resident of the city and county of San Francisco, 5 State of California, have invented a new and useful Carburetor, of which the following is a specification.

This invention relates particularly to a carburetor for the mixture of highly combustible gases and air in such proportions as to secure combustion of the mixture with such degree of pressure as will be safe in the operation of internal combustion engines.

With the rapidly decreasing supply of liquid fuel for consumption in internal combustion engines and with the consequent increase in the cost of the fuel now marketed, it becomes desirable to utilize other and cheaper kinds of fuel.

20 It is therefore, one of the objects of the present invention to provide means for the practical utilization of a highly combustible gas or gases for the operation of internal combustion engines.

25 It is another object of the present invention to provide means for properly mixing a highly combustible gas and air so that the mixture can be safely introduced into and exploded in the chambers of combustion engines at degrees of pressure not above the danger limit.

30 A further object of the invention is to provide for the automatic reduction of the pressure of a gaseous combustible fuel from a source in which it is compressed to comparatively high degree, and for maintaining a supply of the combustible gas at a reduced pressure, and for automatically admitting it into a mixing chamber to be mixed with a proper proportion of air.

35 A further object of the invention is to provide a carburetor for mixing a highly combustible gas with air, and to provide means for controlling the admission of a combustible gas from a supply under considerable pressure into a reduced pressure chamber, and further to provide means for regulating or varying the proportion of gas and air in a mixing chamber.

40 Further it is an object of the invention to provide an automatically acting, pressure reducing means and to provide for the manual control or adjustment of said means.

45 Another object of the invention is to pro-

vide a carburetor of compact construction and organization, of simple elements and which provide for the ready inspection, removal and renewal of the parts as may be necessary.

60 The invention possesses other objects and features of advantage, some of which, with the foregoing, will be made manifest in the following description of the preferred form of the invention which is illustrated in the drawings accompanying and forming part 65 of the specification. It is to be understood that it is not intended to limit the invention to the embodiment shown by the said drawings and description as variations may be adopted within the scope of the invention as set forth in the claims.

70 Referring to the drawings:

Fig. 1 is a plan view of the improved carburetor.

75 Fig. 2 is a central, axial section of the same.

80 Numerous kinds of highly explosive or combustible gases are easily obtained and several are now commercially marked and 85 distributed in containers in which the gases are maintained under comparatively high pressure. Acetylene or calcium carbide gas, is a common and well known combustible medium readily obtainable in the open market, and the present invention has for 90 its purpose to enable the utilization of acetylene or other gas for the operation of internal combustion engines.

95 The present invention embodies a carburetor in which there is a mixing chamber with a suction or outlet port through which a combustible mixture can be drawn into an engine; means being provided for the admission of the combustible gas and a proper proportion of air into the mixing chamber. Further, the invention embodies means for the automatic reduction of the pressure of the combustible gas in cases where the carburetor is receiving the gas from a source of 100 supply in which the gas is under considerable pressure. Means are also provided for manually regulating or controlling the pressure reducing mechanism, and also for controlling the richness of the mixture independently of the gas controlling mechanism.

105 The carburetor as shown, comprises a body or shell 2 of any suitable material and proportions, and is provided with an air inlet flue or passage 3 in which there may be pro-

vided a suitable form of valve 4 arranged on a rock shaft 5 to which is connected a lever 6 from which extends a reach link 7 by the operation of which the position of the valve 4 may be controlled. The air passage 3 leads into a mixing chamber 8 into which the flow of air is controlled by an automatic valve 9.

The mixing chamber 8 is provided with a port 10 closable by a valve 11 and communicating with reduced-pressure gas chamber 12. The wall of the reduced-pressure chamber 12, opposite to the valve 11, may be provided with a removable plug 13 covering an opening through which the valve 11 may be inserted and removed.

A combustible gas from any source of supply may be introduced into the reduced-pressure chamber 12 at a desired degree of pressure and will, when the valve 11 is opened, pass into the mixing chamber 8 and mix therein with air admitted into the mixing chamber when the air valve 9 is opened.

Preferably the valves 9 and 11 are concurrently operable and are therefore suitably connected to move together. The valve 11 is shown as provided with a stem 14 passing through a bearing 15 and on which stem the valve 9 is mounted in a variable or adjustable position with respect to the valve 11, such position being determined by the stop collar 16. The lower end of the stem 14 passes through a bearing 17, disposed in the air intake flue 3.

As it is preferred that the combustible gas be maintained in the pressure chamber 12 at a pressure somewhat above that existing in the mixing chamber 8 during the operation of the engine, the valves 11 and 9 are preferably of differential area; the air valve being the larger so that upon suction in the mixing chamber, which has a suction outlet 18, atmospheric pressure against the air inlet valve 9 causes it to rise admitting air to the mixing chamber and at the same time lifting the gas valve 11 from its seat and allowing gas to flow into the mixing chamber.

A further and important feature of the invention is provision for automatically delivering into the gas chamber 12 a supply of gas from a source, such as a tank not shown, in which the gas is maintained at a considerable pressure. Such provision for admitting gas to the gas chamber also is designed to automatically reduce the pressure from the source of supply to the desired degree in the gas chamber 12. There is therefore provided, relative to the gas chamber 12 a gas inlet port 20 leading from a chamber 21 in which is a piston valve 22 arranged on a stem 23 extending upwardly through a cap or bearing 24. The outer end of the valve stem or rod 23 is provided

with a sliding collar 25 opposed on opposite sides by springs 26 and 27, the latter bearing against an adjustable nut 28 on the threaded end 29 of the valve rod. The spring 26 reacts against a collar 30 on the valve rod. The valve rod 23 projects from one side of the piston valve 22 and has a reduced portion 23' passing through an axial, constricted port 31; one side of the port 31 being provided with a seat 32 to receive a valve 33 mounted on the end of the stem 23' and which valve operates in a high-pressure gas inlet chamber 34. The valve 33 and connected piston 22 comprise a differential valve. Gas under high pressure may be supplied to the chamber 34, suitable connections 35 leading to a gas tank not shown.

In the operation of the engine any desired degree of pressure may be maintained in the gas chamber 12 by the regulation of the pressure of the spring 26 on the collar 30 of the valve stem 23, this pressure tending to open the valve 33 against the pressure of the gas in the chamber 34. Manual or other control of the pressure of the spring 26 is secured by attaching to the sliding collar 25 a link or links 36 attached to a lever 37 on a shaft 38, the lever having an arm 39 attached to a reach link 40 that may be extended to within convenient reach of the operator. Movement of the adjustable pressure collar 25 down upon the spring 26 causes it to react and press the valve 33 from its seat admitting gas into the valve chamber 21, thence through the port 20 into gas chamber 12. As pressure accumulates in the chamber 21 sufficiently to overcome the pressure of the spring 26, the valve 33 is again closed this being accomplished by the pressure of the gas upon the piston portion 22 of the differential valve. It will therefore be seen that upon setting of the regulator 25, a substantially constant pressure will be maintained in the gas chamber 12 by the opening and closing of the valve 33 in consequence of escape of gas as the valve 11 opens to admit it into the mixing chamber 8.

The richness of the mixture in the chamber 8 may be controlled by the adjustment of the air valve 4 since the closing movement of this valve will decrease the quantity of air passing around the valve 9 which is opened by suction in the mixing chamber 8 while a substantially constant proportion of gas is admitted by the valve 11 when it opens.

What is claimed is:

1. A carburetor for mixing a combustible gas from a supply under pressure and air at about atmospheric pressure, comprising a casing having a mixing chamber with a suction outlet and an air inlet, a gas chamber, differential valvular means for stepping down the pressure of said combustible gas

and admitting it to said gas chamber, and automatic, combined differential valves for admitting air, and gas from the gas chamber, to the mixing chamber.

5. 2. A carburetor for mixing a combustible gas from a supply under pressure and air at about atmospheric pressure, comprising a casing having a mixing chamber and a gas chamber, coordinated valves for regulating 10 the flow of gas from the gas chamber and the flow of air to said mixing chamber, a high pressure gas inlet, a differential valve controlling the gas flow from said inlet to said gas chamber, a spring tending to open 15 said differential valve and means for varying the tension of said spring.

3. A carburetor for mixing a combustible gas from a supply under pressure and air at about atmospheric pressure, comprising a 20 casing having a mixing chamber and a gas chamber, co-ordinated valves for regulating the flow of gas from the gas chamber and the flow of air to said mixing chamber, a high pressure gas inlet, a differential valve 25 controlling the gas flow from said inlet to said gas chamber, and means for varying the operative pressure of said differential valve.

4. A carburetor for mixing a combustible 30 gas from a supply under pressure and air

at about atmospheric pressure, comprising a casing having a mixing chamber and a gas chamber, co-ordinated valves for regulating the flow of gas from the gas chamber and the flow of air to said mixing chamber, a high 35 pressure gas inlet, a differential valve controlling the gas flow from said inlet to said gas chamber and having a stem thereon, a collar loose on said stem, a spring interposed between said collar and said stem on both 40 sides of said collar, and means for moving said collar to vary the position of said differential valve.

5. A carburetor for mixing a combustible gas from a supply under pressure and air 45 at about atmospheric pressure, comprising a casing having a mixing chamber and a gas chamber, co-ordinated valves for regulating the flow of gas from the gas chamber and the flow of air to said mixing chamber, a 50 high pressure gas inlet, a differential valve controlling the gas flow from said inlet to said gas chamber, means for bodily shifting said differential valve and resilient means interposed between said differential valve 55 and said shifting means.

In testimony whereof, I have hereunto set my hand.

JEAN B. DUTOUR.
